(57) **CLAIM**

The ornamental design for a charging holder for a mobile phone, as shown and described.

DESCRIPTION

FIG. 1 is a perspective view of a charging holder for a mobile phone;

FIG. 2 is a front view of the charging holder for a mobile phone of FIG. 1;

FIG. 3 is a rear view of the charging holder for a mobile phone of FIG. 1;

FIG. 4 is a left-side view of the charging holder for a mobile phone of FIG. 1;

FIG. 5 is a right-side view of the charging holder for a mobile phone of FIG. 1;

FIG. 6 is a top plan view of the charging holder for a mobile phone of FIG. 1;

FIG. 7 is a bottom plan view of the charging holder for a mobile phone of FIG. 1; and,

FIG. 8 is a perspective view of the charging holder of FIG. 1 to which a mobile phone is docked.

The broken lines showing a mobile phone in the drawings are included for the purpose of illustrating environmental structure and form no part of the claimed design.
